HIDEAWAY FREEZER

Starlin C. Helton, 384 Grand St., Pierson, Mich.
Filed Nov. 26, 1962, Ser. No. 240,014
6 Claims. (Cl. 62—259)

This invention relates to a refrigeration unit, and particularly to a freezer or related unit which provides refrigerated food storage space without consuming valuable living space.

Food storage by refrigeration is accepted today as a necessity. Each year the cubic feet of refrigerator and freezer space used in homes, ships, restaurants, hotels, etc. becomes greater and greater. Consequently, refrigerators and freezers normally assume a great deal of valuable space. In fact, many families today have been forced to put the home freezer in the basement or in the garage to provide sufficient living space in the regular part of the house. Although this remote location of the freezer does indeed provide more floor area or living space, it also necessarily creates an inconvenience directly proportional to the remoteness of the unit. In other locations such as ships, all floor area is valuable and its usage for refrigeration detracts from other potential uses.

It is therefore the main object of this invention to provide a refrigeration-type unit, especially a freezer, that is adapted to be located at a normally remote location for storage, during which no valuable area or living space is consumed, but which is completely convenient for removal or insertion of food within a fraction of a second, and without requiring walking out to the garage or down to the basement or elsewhere, indeed without any extra steps whatever. The unit is normally out of sight, but is within convenient reach right in the kitchen or the like as soon as it is needed. In fact, no bending is required to insert or remove goods. It can be loaded and unloaded from the side, rather than from the top, thereby enabling neat stacking and manipulation of the food stuffs without wasted space, in spite of the fact that no bending is needed to use even the lowermost shelves. The unit is moreover out of the reach of children.

It is another object of this invention to provide an overhead refrigeration unit that, although of considerable size, does not detract aesthetically from the room, and in fact adds not only aesthetic qualities but also serves as a light source for the room.

These and other objects of this invention will be apparent upon studying the following specification in conjunction with the drawings in which:

FIG. 1 is a side elevational view of the novel refrigeration unit shown mounted above the ceiling of a room, and having its inner multiple shelf unit lowered into loading or unloading position;

FIG. 2 is a side elevational view of the portion of the apparatus below the ceiling line during normal storage condition;

FIG. 3 is a perspective view of a portion of the inner mechanism of the apparatus in FIG. 1;

FIG. 4 is a sectional view taken on IV—IV of FIG. 1;

FIG. 5 is a partial electrical diagram of the hoist motor and actuator of the apparatus.

Basically, the inventive refrigeration unit comprises an open bottom, insulated wall and top housing having mounting means on the lower end thereof attachable to the joints in a house above the ceiling, refrigeration equipment operably associated with the housing, preferably in the top thereof, a multiple shelf, foodstuff storage unit normally positioned inside the housing substantially above said ceiling and out of said room, and being in telescopic relationship with the housing to be lowered out of it through an opening in the ceiling for removal or inser-

2

tion of food onto the trays through special doors. The bottom of the tray unit is insulated to close the open bottom on the housing for retention of cold air therein. Between the shelf unit and the top of the housing is a hoist mechanism for lowering the shelf unit through the ceiling into reach inside the room and for raising the unit back up into storage position. Telescoping, centrally-positioned sheath elements around the suspension element of the hoist are located between said housing and shelf rack to stabilize the lowering shelf unit. In addition, peripheral roller elements between the shelf unit and housing guide the shelf during lowering and raising.

Referring now specifically to the drawings, the novel freezer or other refrigeration unit 10 comprises a main housing 12, a telescopically interfiting foodstuff holding shelf unit 14, refrigeration unit 16, cooling coils 17, and hoist mechanism 18.

Housing 12 has an open bottom and is adapted to be mounted above the ceiling 20 by securing it to reinforced joists 22 beneath which the ceiling 20 is suspended. The connection means between the lower end of the housing and the joists is by means of an annular or other configurated metallic support flange 24 riveted or otherwise secured to the periphery of the housing 12, and adapted to rest on and be supported by joists 22. Other support means can be used as necessary. The housing is thus supported above the ceiling over an opening cut into the ceiling and coinciding with the open bottom of the housing to enable shelf unit 14 to be lowered through the ceiling.

If desired, the lower portion 12' of the housing may extend slightly beneath the ceiling level and may even include suitable lights 26 to provide an attractive and even useful appearance to the lower end when normally in its retracted storage position substantially above the ceiling. A peripheral dress ring 30 extends around the lower end of the housing to cover the rough opening cut into the ceiling.

The walls of housing 12 are insulated with a heat barrier layer 32 such as polyurethane foam, polystyrene foam, Fiberglas or other known suitable insulation material. The top of the storage chamber 34 in the housing also includes a suitable layer 36 of insulation.

Operably associated with the storage chamber 34 is a refrigeration unit 16. It may be of any suitable known type, such as Freon the liquid compression, expansion, and evaporation type, or the gas burner evaporation and condensation type as is desired. The arrangement of cooling coils in the chamber 34, and the location of a burner unit, motor, or other units may vary depending upon the type of refrigeration unit, and the principles of operation. Since this may vary widely and the technology regarding these units is well-known, any further detailed explanation is believed superfluous and unnecessary. The refrigeration unit is preferably located in the top of the housing on rigid support plate 38 above insulation layer 36. The housing cap enclosing the refrigeration unit 16 includes outlet vents 40 for dissipation of heat.

The shelf unit 14 is supported on a central column or post 42 affixed at its lower end to bracket 54 and bottom plate 50. Sleeve 42 telescopically interfits around upper sleeve 44. Sleeve 44 may be threadably attached to a collar 46 which is rigidly secured to plate 38. At the lower end of the shelf unit 14 is the insulated bottom closure plate 50, which serves both as the support for the shelf unit, and when the shelf unit is retracted, as a sealing closure for open bottomed housing 12. Plate 50 is filled with any suitable heat insulation material to retain the cold in chamber 34 when the shelf unit is retracted upwardly. A suitable rubber or plastic seal 52 of annular configuration and having some compressibility for

optimum sealing characteristics is located between the upper peripheral surface of bottom 50, and the lower peripheral edge of housing 12, to sealingly close the chamber 34 when the unit is in normal storage condition.

Rigidly secured to the upper surface of the solid plate 50 is the support bracket 54 to which sleeve 42 is attached at its lower end, and which also includes a cross bar 56 or other suitable means interfitting with the suspension chain element 58 of hoist unit 18, and more specifically with hook 59 at the lower end of the chain. In this form of the invention, the suspension chain is adapted to be hoisted by the sprocket 60 and passes into a suitable chain hoist compartment 21 when the sprocket is actuated by a reversible electrical motor 62 mounted upon plate 38. Other equivalent hoist mechanisms may be substituted for the chain hoist and motor combination illustrated, without departing from the principles of the invention as taught.

Serving at the top of the shelf unit and mounted to the top of central sleeve 42 is a lateral guide element in the form of a disc 64 rigidly secured to collar 66, which is threadably connected or otherwise suitably supported on sleeve 42. Mounted in the periphery of disc 64 is a plurality of roller guide elements 68 interfitting in longitudinal tracks 70 in the inner peripheral wall surface of housing 12. These guide the shelf unit against lateral movement as it is raised and lowered into and out of housing 12. Disc 64 includes a plurality of openings 72 to enable the refrigerated air from refrigeration unit 16 to pass freely into the shelf unit. It will be understood that instead of the disc 64, other suitable support means may be positioned between the upper end of sleeve 42 and the inner wall of the housing to laterally guide the structure and help stabilize it as it is being raised and lowered. Any conventional safety stop means (not shown) may be employed to prevent an accident in case of hoist failure.

Attached at spaced intervals up sleeve 42 are shelves 80, 80' and 80", which, together with the upper surface of bottom 50, support foodstuffs to be stored in a refrigerated condition. The food is retained on the shelves out of contact with the housing during raising and lowering by a plurality of arcuate doors 82, which slide in tracks above and below it in the shelves to allow removal or insertion of foodstuffs as needed. These provide convenient side entry enabling neat stacking of foodstuffs. These closure doors may be made of any suitable material such as glass or plastic, or may be a mesh formed of metal strips 86.

As illustrated by way of example in FIG. 5 the reversible hoist motor 62 is connected to a double-throw switch 90 from a conventional power supply 92. Thus, by throwing the switch across leads 94, the motor is actuated to lower the chain, and with it shelf unit 14. Sleeves 42 and 44 act as a sheath for the suspension element 58. Connection of leads 96 to the switch operates the motor in reverse direction to hoist the chain and shelf unit inside the housing to the storage position illustrated in FIG. 2.

Operation

It will be readily understood from the above description that when the freezer or refrigeration unit is in its normal storage condition, the shelf unit 14 is retracted up into housing 12 substantially above the ceiling 20, with optionally a small portion protruding below the ceiling for decorative and lighting purposes. In this storage condition the insulated bottom 50 compresses peripheral seal 52 against the lower edge of the housing shell and closes the open bottom of the housing to provide a sealed chamber 34 refrigerated by unit 16. The unit is out of the way in the attic or the like and assumes no valuable floor space in the kitchen or other rooms. When it is desired to remove foodstuffs from the shelves, or to insert new goods onto the storage shelves, switch 90 is thrown to create a circuit across leads 94 from the power source 92 to motor 62. This causes the motor to rotate sprocket

60 and lower the suspension chain 58 inside the sheath elements. The chain lowers bottom 50 since it is connected around cross bar 56 by hook 59. This allows the bar, bracket 54 and bottom 50 to be lowered, which thereby lowers mounting sleeve 42 and the plurality of shelves 80, 80' and 80". Since the sleeves 42 and 44 telescopically interfit with each other, they provide stability to the unit during this movement. Also, rollers 68 ride along in their respective tracks 70 to laterally guide the unit and also help stabilize it.

When the hoist is completely lowered, switch 90 is released, whereby it moves to its open position illustrated in FIG. 5.

Then one merely slides back the particular door 82 of the shelf concerned, removes or inserts goods, or re-closes the door. Then by throwing the switch 90 to connect leads 96 and reverse the hoist motor, chain 58 is retracted to hoist the bottom 50, column sleeve 42 and the sleeves until the upper annular surface 51 of the bottom presses against the seal 20 on the lower end of the housing to close the chamber again. It is thus completely out of the way again, and largely out of sight. In fact, it appears merely as a normal light in the ceiling of the home. It therefore moves from a storage position which is completely remote and utilizes no valuable floor area or living space to a position at a convenient height enabling side removal and insertion of goods, and not requiring any bending to reach the lower shelves.

Although the cylindrical configuration described and shown is the preferred form, it will be readily understood that the cross sectional configuration of the unit may be rectangular, triangular, or polygonal. Of course, the doors 82 will be shaped accordingly. Various other obvious modifications may be made in the structure within the principles of this invention. Therefore the invention is not to be limited by the exemplary structure illustrated, but only by the scope of the appended claims, and the reasonably equivalent structures to those defined therein.

I claim:

1. A refrigeration unit for overhead mounting in a room, comprising: a housing having mounting means on the lower end thereof for mounting said housing to ceiling joists above the ceiling in a room; said housing having insulated walls and top defining a storage chamber; refrigeration equipment operably associated with said chamber to cool the air therein; said housing and chamber having an open bottom adapted to coincide with an opening in said ceiling; a foodstuff storage unit normally positioned in said housing to be overhead of and substantially out of said room; the bottom of said unit being insulated to close the open bottom of said housing when in the normal storage position; said unit being in telescopic relationship inside said housing and operably connected thereto by elevating means; and actuator means for reversibly operating said elevating means to lower said unit largely out of said housing and into the room for removal or insertion of foodstuffs, and to raise said unit back into storage position again inside said housing.

2. An overhead foodstuff refrigeration unit in a room, comprising; support joists having the ceiling of said room suspended therebeneath; an opening in said ceiling; an insulated, open bottom, housing mounted to said joists above said ceiling around said opening and normally out of sight; a refrigeration unit operably associated with said housing to refrigerate the interior thereof; a storage unit normally retained in said housing, and having an insulated bottom to close the open bottom of said housing when in the storage position; a peripheral air seal between said bottom and said housing to normally retain the cold air in said housing; and motor operated hoist means connected between the top of said housing and said shelf unit to enable said shelf unit to be lowered within reach of someone in said room, and to be hoisted out of reach and into a storage position.

3. A ceiling refrigerator comprising: an open bottom,

insulated housing including mounting means to fixedly attach it above the ceiling and substantially out of sight in a room; refrigeration means to cool the housing interior; storage shelf means normally retained in said housing substantially above said ceiling and including food retention doors; an insulated portion of said shelf means normally forming the bottom of said housing; hoist means to lower said shelf means out the open bottom of said housing and into the room for opening said doors for removal or insertion of food, and raise said shelf means into a refrigerated storage position inside said housing; and guide means between the periphery of said shelf means and said housing to guide said shelf means as it is lowered and raised.

4. A ceiling refrigerator comprising: an open bottom, insulated housing including mounting means to fixedly attach it above the ceiling in a room; refrigeration means to cool the housing interior; storage shelf means normally retained in said housing substantially above said ceiling and including food retention doors; a portion of said shelf means normally forming the bottom of said housing, hoist means including a suspension element attached to said shelf means to lower said shelf means out the bottom of said housing and into the room for opening said doors for removal or insertion of food, and raise said shelf means into a storage position; centrally positioned, elongated members telescopically interfitted and attached respectively to said shelf means and said housing to stabilize movement of said shelf means with respect to said housing and enclosing the suspension element of said hoist means.

5. A ceiling refrigerator comprising: an open bottom, insulated housing including mounting means to fixedly attach it above the ceiling in a room; refrigeration means to cool the housing interior; storage shelf means normally retained in said housing substantially above said ceiling, and including food retention doors; a portion of said shelf means normally closing the bottom of said housing; hoist means including a suspension element attached to said shelf means to lower said shelf means out the bottom of said housing and into the room for opening said doors for removal or insertion of food, and re-raise said shelf means into a storage position inside said housing; centrally positioned, elongated members telescopically interfitted

and attached respectively to said shelf means and said housing to stabilize movement of shelf means with respect to said housing and enclosing the suspension element of said hoist means; and roller guide means between the periphery of said shelf means and the interior of said housing to guide said shelf means as it is lowered or raised.

6. A refrigeration unit for overhead mounting in a room, comprising: a housing having mounting means on the lower end thereof for mounting said housing to ceiling joists above the ceiling in a room; a portion of the lower end of said housing adapted to extend below an opening in said ceiling when so mounted; light means in said portion to enable it to serve a decorative lighting purpose; said housing having insulated walls and top defining a storage chamber; refrigeration equipment operably associated with said chamber to cool the air therein; said housing and chamber having an open bottom; a foodstuff storage unit normally positioned in said housing to be overhead of and substantially out of said room; the bottom of said unit being insulated to close the open bottom of said housing when in the normal storage position; said unit being in telescopic relationship inside said housing and operably connected thereto by elevating means; and actuator means for reversibly operating said elevating means to lower said unit largely out of said housing and into the room for removal or insertion of foodstuffs, and to raise said unit back into storage position again inside said housing.
